UNITED STATES PATENT OFFICE.

ENEAS LINTZ, OF RIO DE JANEIRO, BRAZIL.

LIFE-SAVER THAT SERVES ALSO AS A BUFFER.

Application filed April 16, 1928, Serial No. 270,554, and in Brazil May 11, 1927.

The object of the present invention is a life-saver characterized by the fact that it serves as a buffer on account of its construction and disposition of its parts, and it may be rapidly turned into a life-saver or vice-versa.

In the drawings, Fig. 1 is an elevation of my invention applied to a vehicle, and in closed position to form a bumper or buffer. 10 Fig. 2 is a plan view of the same.

Fig. 3 is a view similar to Fig. 1 but with my device in open position to form a life-saver.

In order to be clearly understood, the accompanying drawing shows in Fig. 1 the fore-part of a motor-car, *a* designating two holder-bars fixed to the under-frame, having in their ends two other right angled bars *b* each of said bars has one of its arms in vertical position. These bars are intended to support the whole apparatus, the movement proceeding from the main axle *c* on which axle are fixed arms *y* attached to members *d*, Fig. 3, forming a holder *f*, articulated with 25 the lower arm *e*, supporting in the fore end thereof the lower part of the buffer.

The upper end of arm *e* joins with the bar *f* in L shape, which rotates on the pin *g* screwed in the upstanding bar *b*, the other 30 end of bar *f* being connected to the upper arm *h* through the articulating bar *i*. The arm *h* pivots on the pin *j* as a support and is intended to open the buffer, which includes a metal plate *k* and an angle-iron *l*, both 35 fixed at the end of said arm.

The fore-part of the buffer or the lower part of the life-saver is also made of metal plate *m*, riveted in an angle-iron *n*, which articulates with the arm *e* by means of the 40 ears *o* soldered in said angle-iron. In this part of the apparatus there is structure to articulate the lower plate *m* by means of the bars *p* and pins *r*, which are provided, in the center, with two wheels *s* to support 45 the fore part on the ground.

It is easily seen from the embodiment and by the explanations above that this apparatus is adapted, by means of fixed retaining arms *t*, to maintain the buffer closed, and to wrap the canvas *u*, which has the ends fixed 50 to the plates *k* and *m*, having the center part fixed in the angle-iron *v* riveted at the ends of the bars *b*. In this same figure *a'* is a cover made of metal plate to protect articulations. 55

The small conductors or guides *z* and *z'* are provided to facilitate wrapping the canvas. The lever *w*, fixed at the end of the axle, is joined to the bar *x* that moves the apparatus by means of a lever mounted in 60 the chauffeur's cabin.

Fig. 2 represents the life-saver opened showing the canvas *u* unrolled, on which are shown the cross-beams *b'* made of wood, sewed to the canvas in order to maintain 65 it spread and in order to give same more strength. In this same figure *z²*, *z³* and *z⁴* will be seen the guide-bars intended to facilitate wrapping up the canvas.

Fig. 3 is a plan view of the buffer, wrapped 70 up or closed, showing the bars *y* on the axle *c* the object of which is to avoid torsion of the axle with the arms *d*.

Claim:

In combination with a vehicle, a bumper 75 element, folding lever mechanism supporting said element which when in folded condition positions the bumper element to perform its bumping function, means for unfolding the lever mechanism to form a life 80 saver and thereby displacing the bumper element, said bumper element comprising a housing supported on one end of the lever mechanism and a sheet of flexible material connected with said housing at one end and 85 at its other end with the opposite end of the foldable lever mechanism and adapted to be folded in said housing when the lever mechanism is folded.

ENEAS LINTZ.
